Attest,
a. P. N. Van Dusen,
E. M. B. Phillips

Inventor:
Rensselaer Hitt,
by C. B. Brockatty

UNITED STATES PATENT OFFICE.

RENSSELAER HITT, OF WATERLOO, IOWA, ASSIGNOR OF ONE-HALF TO
PETER S. DORLAN, OF SAME PLACE.

WAGON-JACK.

SPECIFICATION forming part of Letters Patent No. 371,887, dated October 18, 1887.

Application filed June 30, 1887. Serial No. 242,984. (No model.)

To all whom it may concern:

Be it known that I, RENSSELAER HITT, a citizen of the United States, residing at Waterloo, in the county of Black Hawk and State 5 of Iowa, have invented certain new and useful Improvements in Wagon-Jacks; and I do declare the following to be a full, clear, and exact description of the invention, such as will enable others skilled in the art to which it applies 10 to make and use the same, reference being had to the accompanying drawings, and to the letters and figures of reference marked thereon, which form a part of this specification.

15 Figure 1 of the drawings represents a wagon-jack embodying my improvements. Fig. 2 is a plan view of the same.

My invention relates to lifting-jacks designed more particularly for the raising and 20 supporting of the axles of vehicles while lubricating the axles and the removal and replacing of the wheels thereon. The invention is, however, capable of other uses.

25 My improvement consists in the following construction and combination of parts, which will first be fully described, and the points of novelty then set forth in the claim.

1 represents a base-plate or bed, which supports the standard 2 and the other parts of 30 the machine. The standard 2 is rigidly bolted to the base, and is provided with a central vertical passage, within which the lifting-bar 3 moves, as will be hereinafter set forth.

35 4 is a cap on top of lifting-bar 3, on which the wagon-axle rests when raised.

5 is a projecting arm at the top of standard

2. It is curved at its inner end, so as to rigidly embrace the standard.

6 is the operating-lever. It is pivoted in the outer end of arm 5 by a pivot, 7, and its 40 inner end is split or bifurcated, so as to clear the arm 5 and the standard 2.

8 is a vertical slot cut entirely through the standard 2.

9 is a cross-head secured to the lower part 45 of the lifting-bar 3 and projecting through both sides of the slot 8.

10 10 are two links arranged on each side of the standard, the upper ends of which are pivoted at 11 11 in the bifurcated ends of lever 6.

12 is a hook-latch pivoted to the lever 6, and adapted to engage the eye or staple 13 when the lifting-bar 3 is raised, and hold it in that position as long as may be desired. 55

What I claim, and desire to secure by Letters Patent of the United States, is—

In a wagon-jack, the combination of a hollow slotted standard open at the top, a lifting-bar working therin, a projecting arm secured 60 to the top of the standard, a bifurcated lever journaled on said projecting arm, and two links secured to each prong of said lever and at their lower ends to opposite sides of said lifting-bar, substantially as set forth. 65

In testimony whereof I affix my signature in presence of two witnesses.

RENSSELAER HITT.

Witnesses:

W. W. EDGINGTON,
DANL. W. FOOTE.
